UNITED STATES PATENT OFFICE.

LEVI W. TARBELL, OF CARLTON, MINNESOTA.

DESIGN FOR A HAMMER-HEAD.

SPECIFICATION forming part of Design No. 35,203, dated October 22, 1901.

Application filed September 16, 1901. Serial No. 75,824. Term of patent 7 years.

To all whom it may concern:

Be it known that I, LEVI W. TARBELL, a citizen of the United States, residing at Carlton, in the county of Carlton and State of Minnesota, have invented and produced a new and original Design for a Hammer-Head, of which the following is a specification, reference being had to the accompanying drawings, forming a part thereof.

Figure 1 is a perspective view of the invention, and Fig. 2 is a sectional view through the same.

As shown in the drawings, the essential feature of the design comprises a head portion 1, from one end of which project two curved claws 2 and 3, formed apart from each other and having their inner sides beveled, as at 4

and 5. The claws are connected near their respective ends by a cross-bar 6, so as to form a dovetail groove 7, said bar being wedge-shaped in cross-section and having a V-shaped slit 8 intermediate its ends.

Having thus fully described my invention, what I claim, and desire to secure by design Letters Patent, is—

The design for a hammer-head, substantially as herein shown and described.

In testimony whereof I affix my signature in presence of two witnesses.

LEVI W. TARBELL.

Witnesses:

D. C. ANDERSON,
FREDA LARSON.
